UNITED STATES PATENT OFFICE.

HARRY FRIED, OF WASHINGTON, DISTRICT OF COLUMBIA.

MATCH-VENDING MACHINE.

Application filed October 20, 1921. Serial No. 509,099.

To all whom it may concern:

Be it known that I, HARRY FRIED, a citizen of the United States, residing at Washington, District of Columbia, have invented a new and useful Improvement in Match-Vending Machines, of which the following is a specification.

This invention relates to improvements in match vending machines, and one of the principal objects is to provide a device of this nature with improved coin-controlled mechanism.

Another object is to provide the device with improved vending mechanism.

Another object is to provide simplified and improved means for preventing the removal of the contents of the machine through the delivery opening without first operating the coin-controlled mechanism.

With these and other objects in view which will be more apparent as the specification proceeds, the invention resides in certain novel construction and combination and arrangement of parts, the essential features of which are hereinafter fully described, are particularly pointed out in the appended claim and are illustrated in the accompanying drawing, in which:

Figure 1 is a front elevation of my improved match vending machine with parts broken away and in section for the sake of clearness.

Figure 2 is a fragmentary vertical section on line 2—2, Figure 1, looking to the right so as to show the coin mechanism.

Figure 3 is a view taken along the same line, but looking to the left so as to show the general construction of the vending mechanism.

Figure 4 is a detail perspective view of one of the weights.

Figure 5 is a detail view of the cam plate.

Figure 6 is a detail view of the clutch disk.

Figure 7 is a detailed view of one of the ejector disks.

Like characters of reference refer to like parts in all views.

Referring to the drawing in detail, 10 represents the base, 11 the sides, 12 the top, 13 the front, and 15 and 16 the upper and lower elements of the back of the main frame of the machine, the members 15 and 16 being preferably hinged at 17 so that member 15 may be lowered to fill the ma-

chine with boxes of matches, and the member 16 may be raised to remove the coins from the coin box. The front 13 is preferably provided with windows 18 whereby the customer may see if the machine is empty or not, and is extended downwardly into an apron 19 which does not reach completely to the base, and below which the packages are delivered to the customer. This vending aperture is masked by a hood member 20 which extends upwardly inside the apron 19 and rearwardly forming a table 21 upon which the boxes or containers are stacked. The table 21 and upper front portion of the member 20 are slotted so as to permit free rotation of the ejectors or vending disks. The apertures at 22 where the containers are forced off the table 21, are just sufficiently high to permit the containers to slip out freely if there is nothing to prevent. Containers are indicated at 23.

Secured to the inner side of the right-hand wall of the machine is a coin chute 24 which communicates at its upper front end with the coin slot in the usual plate 25.

A U-shaped frame 26 is provided and when the machine is complete, this frame is secured to the base 10 of the machine in any desirable manner. Before being placed in the machine, this frame is assembled with the main shaft and most of the mechanism connected therewith. The main shaft is shown at 27 and this shaft is preferably square in cross section except near its ends where it is round so as to turn easily in its bearings. The right hand end of the shaft 27 is rotatably mounted in the hub 28 of the coin disk 29 which will presently be described in detail. This hub 28 is itself rotatable in the right hand end of the frame 26 and has secured to it by a set screw 30 or other suitable means, the operating knob 31. The left hand end of the shaft 27 may be rotatably supported directly in the left end of the frame 26 or in any suitable bearing supported by same frame.

Mounted on the shaft 27 are a plurality of ejector disks 32, which are held in proper relation or "set" by reason of having squared central apertures threaded on the squared portion of the shaft with intervening spacer sleeves. While I have showed four such disks in the drawing, it is to be understood that more or less could be used, but in that

case obvious changes would have to be made in the degree of travel of the shaft at each operation and in the other mechanisms accordingly. The present mechanism is designed to eject one container at each quarter revolution of the shaft 27, and consequently the coin mechanism permits a coin inserted to control only a 90° movement of the shaft after which the coin is dropped into the coin box or receptacle which box is indicated at 33. Each ejector disk is formed with a peripheral flange 34 which gives a considerable breadth to the disk, and a depression 35 is formed of suitable size to permit one of the 15 containers to drop thereinto. The depression 35 is bounded by a comparatively high rear wall 36 and a comparatively low front wall 37. The purpose of the rear wall 36 is to press the container out upon the rotation 20 of the shaft, and the purpose of the front wall 37 is to prevent cheating the machine by inserting the fingers or other instrumentalities in the aperture below the apron 19 and drawing the containers out of the 25 apertures 22. It will be seen that when the arcuate portions of the disk are under the containers, the containers will be held off the table 21 and above the upper margin of the aperture 22 so that they can not be withdrawn, and when they drop into the notches 35, the element 37 will prevent withdrawal 30 of the container until the shaft and ejector are turned.

The coin disk 29 hereinbefore referred to, 35 is constructed with four coin pockets 38 and with concentric ways 39, the pockets 38 being intervened by flanges 40 which prevent a succession of coins being fed into the coin disk between proper operations whereby the 40 mechanism might be clogged or injured. Next to the left of the coin disk on the shaft 27 is the clutch disk. This is indicated by the numeral 41; and in this clutch disk are 45 slidably seated four clutch pins 42 arranged at intervals of 90°. Each pin is formed with a beveled head 43 on one end and a nut 44 threaded on its other end. A spring 45 tends constantly to press the nut 44 outwardly. Notches 46 are formed in the periphery of the disk 41 and co-act with a pawl 47 to prevent turning the disk 41 more than 90° at an operation. This pawl 47 is broad enough to overlie the coin disk 29 so that it will be raised by the projecting edge of the 55 coin in turning the coin disk. A click pawl

48 co-acts with notches 46^a to prevent retrograde movement of the devices.

Rising from the base of the frame member 26 is a cam plate 49, which loosely embraces the shaft 27 and has formed on its face adjacent to the disk 41, a cam having a gradual rise at 50, a dwell at 51 and an abrupt drop at 52. This plate is arranged so that the pins 42 will have their nuts 44 ride up the rise 50 onto the dwell 51 and then drop suddenly upon reaching 52. It will be seen that the dwell 51 is slightly more than a 90° arc so that one or another of the pins 42 will always be in contact therewith.

Upon each stack of containers is placed a weight 53, which has its lower face cut away at 55 so that when the final container has been ejected, the ejector may revolve freely through the way 55 without striking the weight.

In operation, when a coin is inserted, it passes down the chute 24 and lodges in one of the pockets 38 in the coin disk 29. It will be remembered that one of the pins 42 is pressed to the right by the cam 51 and this brings this pin in line with the ways 39 with its head 43 pressed into the path of the coin. The customer then operates the knob 31 by turning it, whereby the coin is brought up so as first to lift the pawl 47 to unlock the vending mechanism, and then into contact with the projected pin head 43. The further progress of the coin disk carries with it the clutch disk and the shaft. As the shaft makes its 90° turn one or another of the ejectors will release a container (these ejectors being set with their portions 25, 90° apart), and the pin on reaching 52 will return by the spring 45, and the coin is released so that it drops from its pocket 95 into the coin box 33.

What I claim is:

In a device of the class described, the combination of a main operating mechanism, ejecting mechanism operable thereby, an operating member, a stationary cam device, a rotary clutch device, pins in said clutch device and controlled by said cam device, and a coin disk having coin pockets formed therein and having a way for receiving said pins.

In testimony whereof, I have signed my name to this specification this 25 day of August 1921.

HARRY FRIED.
